(57) **CLAIM**

The ornamental design for a long arm sewing machine for quilts, as shown and described.

DESCRIPTION

FIG. 1 is a top, front, left perspective view of a long arm sewing machine for quilts, showing my new design;
FIG. 2 is a top, back, right perspective view thereof;
FIG. 3 is a top plan view thereof;
FIG. 4 is a bottom plan view thereof;
FIG. 5 is a front elevational view thereof;
FIG. 6 is a rear elevational view thereof;
FIG. 7 is a right side elevational view thereof; and,
FIG. 8 is a left side elevational view thereof.
The broken lines in the figure drawings represent unclaimed environment and form no part of the claimed design.

1 Claim, 8 Drawing Sheets
